UNITED STATES PATENT OFFICE.

WILLIAM R. DUTEMPLE, OF AUBURN, RHODE ISLAND.

DESIGN FOR A CAMPAIGN BADGE OR PIN.

SPECIFICATION forming part of Design No. 26,013, dated September 15, 1896.

Application filed July 20, 1896. Serial No. 589,974. Term of patent 3½ years.

To all whom it may concern:

Be it known that I, WILLIAM R. DUTEMPLE, a citizen of the United States, residing at Auburn, in the county of Providence and State 5 of Rhode Island, have invented and produced a new and original Design for a Campaign Badge or Pin, of which the following is a specification, reference being had to the accompanying drawing, and to letters of reference 10 marked thereon, which form a part of this specification.

The design is more especially intended to be embodied in a metallic badge or pin representing one or more of the features or issues 15 of the coming political campaign, though it is not intended to be thus restricted.

The design includes the form and representation of a scale or beam *a*, having suspended at one end thereof a comparatively large disk 20 or member *s* and a smaller disk or member

g at the opposite end of the beam. At a point between the said two ends of the beam the latter is represented as being suspended from a pin or holder *p*.

Another feature of the design consists in representing the said disks or members in contrasting shades or colors, as, for example, the larger one *s* may be white or silver color and the smaller one *g* yellow or gold color. The edges or peripheries of the disks or members may be milled or otherwise ornamented.

What I claim is—

The design for a campaign badge or pin, substantially as herein shown and described.

In testimony whereof I have affixed my signature in presence of two witnesses.

WILLIAM R. DUTEMPLE.

Witnesses:

GEO. H. REMINGTON,
REMINGTON SHERMAN.
